DOOR LOCK

Ralph C. Clark, Willowbrook, Calif., assignor to
Ray E. Clark, Willowbrook, Calif.

Application March 12, 1948, Serial No. 14,419

3 Claims. (Cl. 70—146)

1

This invention relates to improvements in locks, and more particularly to an improved mortise lock for a house door.

It is among the objects of the invention to provide an improved lock which may be mounted in a door without the use of any screws threaded into the material of the door and with only two screws in the lock structure itself which may be quickly assembled and disassembled and does not require highly skilled labor for its assembly and installation, which has mutually interlocking parts which secure the lock components together when operatively assembled, which can be knob-operated from either side when unlocked, can be locked from the inside so that it can be operated from the outside only by use of a key, and can also be locked from the inside so that it cannot be operated from the outside, which requires only a circular hole extending through the door and an intersecting bore extending from the edge of the door to the hole for the mounting of the lock in a door, and which is simple, durable and economical in construction, and neat and attractive in appearance.

Other objects and advantages will become apparent from a consideration of the following description in conjunction with the accompanying drawings, wherein:

Figure 1 is a perspective view of the lock in longitudinal cross-section;

Figure 2 is an exploded, perspective view of the lock components in position for assembly;

Figure 3 is a longitudinal cross-section of the lock installed in a door and is taken substantially in the plane of the section line 3—3 of Figure 1;

Figure 4 is a longitudinal cross-section similar to Figure 3, but taken in a plane perpendicular to the sectional plane of Figure 3;

Figure 5 is a transverse cross-section of the lock installed in a door and is taken substantially in the plane of the section line 5—5 of Figure 1;

Figures 6 and 7 are views similar to Figure 5, but showing the latch bolt and bolt-operating spindles in different operative positions from that illustrated in Figure 5;

Figure 8 is a transverse cross-section taken substantially in the plane of the section line 8—8 of Figure 1;

Figure 9 is a transverse cross-section taken substantially in the plane of the section line 9—9 of Figure 1;

Figure 10 is a cross-sectional view of a portion of the inner escutcheon plate showing the application thereto of a slidable pin for locking the inner knob of the lock; and

2

Figure 11 is an elevation of the inner end of the lock showing a modified form of the invention.

With continued reference to the drawings, the improved lock comprises, in general, an outer escutcheon structure 10, a hollow lock bolt housing 11, a latch bolt 12 slidable in the housing 11, a knob spindle 13, an outer knob 14 mounted on the outer end of the spindle 13, an inner knob 15 mounted on the inner end of the spindle, an inner escutcheon plate 16 surrounding the spindle at the inner end of the inner knob, screws 17 operatively connecting the inner knob and inner escutcheon plate to the outer escutcheon structure 10, a lock tumbler barrel 18 secured in a bore in the outer knob, a key cylinder 19 operatively mounted in the tumbler barrel, and a key spindle 20 operatively engaged at one end by the key cylinder 19 and extending through the lock bolt 12. A dead bolt pin 21 extends through the inner escutcheon plate 16 for operative engagement with the latch bolt 12 to secure the lock against operation, and a locking pin 22 is slidably carried by the inner escutcheon plate 16 for locking the knobs and the knob spindle 13 against rotation.

The outer escutcheon structure 10 comprises an escutcheon plate formation 24 in the form of a circular plate having a central aperture 25 surrounded by an external annular boss 26, a pair of diametrically opposed, partly cylindrical segments 27 with substantially parallel, flat inner sides disposed one at each side of the aperture 25, and a semi-circular flange 28 extending inwardly of the aperture or opening 25 at the inner face of the escutcheon plate formation 24. The segments 27 have respective grooves 29 in their inner flat faces parallel to and adjacent corresponding edges of the segments and screw-threaded wells 30 extending inwardly of the segments from the ends thereof opposite the escutcheon plate formation 24. The segments 27 are disposed inwardly of the periphery of the escutcheon plate formation 24 to provide an annular shoulder 31 extending entirely around the inner face of the plate formation, the segments 27 being so spaced as to fit into a circular hole provided in a door and the shoulder 31 being adapted to bear against the door surface surrounding the hole at the outer side of the door. The length of segments 27 is such as to extend substantially through a door of the minimum thickness to which the lock is to be applied. The lock, however, is readily adaptable to thicker doors without in any way changing the structure thereof, as will presently appear.

The outer knob 14 is provided with a cylindrical axial bore 32 extending therethrough and surrounded at the inner side of the knob by an annular boss 33 and a semi-circular flange 34 extending inwardly of the aperture at the inner end of the boss.

The lock tumbler barrel 18 and key cylinder 19 are of conventional construction and do not require a detailed description. The tumbler barrel 18 is secured in the bore 32 of the knob against rotation relative to the knob and is provided with spaced-apart radial bores in which conventional tumblers 33 are slidably received and in which the tumblers are held by a dovetailed plate 134 slidably received in a dovetailed groove provided in the barrel at the outer ends of the tumbler bores. The key cylinder 19 is normally held against rotation in the barrel 18 by the tumblers 33, but may be rotated by the proper key when inserted into the cylinder in the conventional manner. The inner end of the key cylinder has an apertured lug 35 thereon operatively connecting the key cylinder to the key spindle 20.

The knob spindle 13 comprises a semi-cylindrical intermediate portion 36 having a semi-cylindrical concavity 37 in the flat face thereof, a semi-cylindrical flange 38 at the outer end of the portion 36 and an elongated, square or non-circular shank 39 extending from the inner end of the semi-cylindrical portion 36 substantially coaxially therewith. The semi-cylindrical cavity 37 terminates in a perpendicular shoulder 40 spaced from the inner face of flange 38 and a semi-cylindrical concavity 41 of materially smaller radius than the radius of the concavity 37 extends from the shoulder 40 to the flanged outer end of the spindle.

The key spindle 20 comprises a semi-cylindrical end portion 42 receivable in nesting association in the concavity 37 of the knob spindle 13, a cylindrical intermediate portion 43 which fits in the smaller concavity 41 of the knob spindle, and an enlarged cylindrical end portion 44 having a diameter substantially equal to that of the flange 38 of the lock spindle and having a non-circular recess 45 in the outer end thereof into which the lug 35 of the key cylinder 19 fits.

The outer escutcheon structure 10, knob spindle 13, key spindle 20, knob 14, tumbler barrel 18 and key cylinder 19 are operatively associated in the following manner to provide a primary sub-assembly.

First, the key cylinder 19 is placed in operative position in the tumbler barrel 18. The lug 35 of the key cylinder is then inserted into the recess 45 in the end portion 44 of the key spindle 20 and a locking pin in the form of a screw 46 is inserted through a diametrical aperture 47 in the socket 44 and through the aperture in the key cylinder lug 35 thus positively connecting the key cylinder to the key spindle. The key spindle 20 is then nested in the lock spindle 13 and this entire structure is inserted through the outer knob 14 from the outer end of the knob, until the flange 38 of the knob cylinder is in alignment with the semi-circular flange 34 at the inner end of the knob bore with the ends of the flanges mutually opposed to hold the knob spindle against rotation relative to the outer knob 14. It is understood that when the tumbler barrel 18 is inserted into the knob bore, it is secured against rotation relative to the knob by some convenient means, such as interfitting, non-

circular portions of the bore and the tumbler barrel.

With the spindles and the tumbler barrel and key cylinder held in operative position in the outer knob, the ends of the spindles projecting from the inner end of the knob are now inserted through the central aperture 25 in the escutcheon structure 10 in an inverted position such that the aligned flat faces of the semi-circular portions of the spindles pass over the shoulders of the flange 28 in the escutcheon plate formation of the lock barrel. When the outer end of the boss 26 of the escutcheon plate formation 24 is brought into contact with the inner end of the knob boss 33, the semi-circular flange 28 will be in alignment with a circumferential groove 48 provided in the outer surface of lock spindle 13 adjacent the inner face of flange 38. The knob and spindle assembly is now rotated through 180° seating the flange 28 in the groove 48 to secure the knob and spindle assembly against separation from the outer escutcheon structure 10. This sub-assembly is now ready for the association of the latch bolt housing and latch bolt therewith.

The latch bolt housing 11 is an elongated tubular member of rectangular cross-section having transverse grooves 50 in its normally upper and lower outer faces providing shoulders 51 which are slidably received in the grooves 29 of the structure 10. At its outer end, the housing 11 is provided with an outwardly-extending flange or shoulder 52 received in a recess provided in the edge of the door surrounding the outer end of a bore 53 provided in the door to receive the latch housing 11. If desired, brads or screws 54 may be inserted through suitable apertures in this shoulder and into the door to assist in holding the housing in operative position in the bore. This housing is provided intermediate the length of opposite sides thereof with elongated openings 55 for a spring stop plate 56, the purpose of which will be further described in connection with the construction of the latch bolt 12, and with an aperture 57 for the inner end of the dead bolt pin 21.

The latch bolt 12 comprises an elongated member of rectangular cross-section having its outer end beveled at one side, as indicated at 58, and having an elongated spring-receiving slot 59 intermediate the length thereof, a spindle-receiving slot or opening 60 of substantially square shape near the rear end thereof, and a hole 61 to receive the inner end of the dead bolt pin 21.

The latch bolt housing 11, latch bolt 12 and latch bolt spring 62 constitute a second sub-assembly provided by placing the spring in the spring-receiving slots 59 in the latch bolt, inserting the latch bolt in the housing, and then inserting the spring abutment plate 56 through the housing openings 55 at the rear end of the spring, so that the compression spring 62 will be operative to resiliently force the latch bolt outwardly of the housing to the operative position illustrated in Figure 5.

In order to assemble the latch bolt sub-assembly with the primary sub-assembly described above, the latch bolt housing is inserted in the bore 53 provided therefor in the door with the shoulders at the inner end thereof positioned at the corresponding side of the hole 63 provided in the door for the lock barrel 10. With the latch bolt and housing assembly in position, the outer escutcheon structure is then inserted in

the hole 63 and the grooves 29 slidably receive the shoulders 51 to positively secure the latch bolt housing to the outer escutcheon structure. Movement of the latch bolt 12 in the housing 11 is limited by a stop pin 64 extending through an elongated slot 65 in the latch bolt and having its ends secured in apertures provided in the opposite side walls of the latch bolt housing. When the barrel is being inserted in the hole 63 in the door, the latch bolt is preferably forced rearwardly against the action of spring 62 so that the spindles 13 and 20 will pass freely through the spindle-receiving slot 60 in the latch bolt. Once the spindles are in operative position in the slot 60, the pin 64, restricting rearward movement of the latch bolt, will prevent the knob spindle 13 from being rotated to an extent such that it can be disassociated from the barrel structure 10.

After the primary sub-assembly, including the lock barrel, spindles and outer knob, has been operatively associated with the secondary sub-assembly, including the latch bolt and latch bolt housing, the inner knob 15 and inner escutcheon plate 16 are sub-assembled and then associated with the primary sub-assembly.

The inner escutcheon plate 16 comprises a flat, circular plate structure having a central aperture 66 surrounded at the outer side of the plate by a boss 66, eccentric apertures 67 for the screws 17, a radial groove 68 in its inner face in which the locking pin 22 is slidably mounted, and an aperture 69 for the dead bolt pin 21.

The inner knob 15 has a cylindrical shank 10 provided with angularly-spaced, radial holes 71 to receive the inner end of the locking pin 22 and with a circumferential groove 72 spaced outwardly from these holes. This knob also has an elongated axial well 73 of the same cross-sectional shape and size as the cross-sectional shape and size of the shank 39 of the knob spindle 13. In order to assemble the inner knob 15 with the inner escutcheon plate 16, the knob shank is inserted through the central opening in the plate, a suitable thrust washer 74 is placed over the shank to bear against the inner side of the escutcheon plate, and a snap ring 75 is secured in the circumferential groove 72 holding the knob in operative association with the escutcheon plate.

After completing the inner knob and escutcheon plate sub-assembly, this sub-assembly is associated with the primary sub-assembly by inserting the inner end of shank 39 in the well 73 in the inner knob and moving the inner knob toward the outer knob until the inner escutcheon plate 72 bears against the inner face of the door. The screws 17 are then inserted through the corresponding holes in the inner escutcheon plate and threaded into the screw-threaded holes 30 provided in the segments 21 of the lock barrel and tightened until the door is firmly clamped between the inner escutcheon plate 17 and the outer escutcheon plate formation 24 of the lock barrel structure. The lock is now completely assembled in the door. The length of screws 17 is sufficient to compensate for different door thicknesses.

When the lock is free, the knob spindle 13 may be rotated by either the outer or inner knob. The semi-cylindrical portion or cam 36 is disposed with its flat face against the flat inner end of the spindle-receiving slot 60 in the latch bolt, so that when the knob spindle is rotated, the latch bolt will be moved rearwardly, as is

particularly illustrated in Figure 6. When the knob spindle 13 is thus rotated by either the inner or outer knob, the key spindle 20 will also be rotated, but has no operative function at this time.

When it is desired to lock the door so that it can be opened from the outside only by use of a key, the locking pin 22 is moved inwardly by suitable means, such as the toggle lever 76, until its inner end is engaged in one of the radial holes 71 provided in the shank of the inner knob. With the inner knob thus locked against rotation, the knob spindle 13 cannot be rotated and the door cannot be opened by the outer knob, or by either knob until the locking pin is withdrawn. If it is now desired to open the door from the outside, a key 77 is inserted in the key cylinder 19 and rotated, which operation will rotate the key spindle 20, as particularly illustrated in Figure 7, moving the latch bolt 12 rearwardly sufficiently to release the lock. If it is desired to secure the door so that it cannot be opened with a key from the outside, the dead bolt pin 21 is pushed inwardly so that its inner end engages in the corresponding hole 61 in the latch bolt in which case the latch bolt cannot be withdrawn by either the knobs or a key.

In the modified form of the invention illustrated in Figure 11, the inner knob 15 is omitted and a hub member 80 is secured on the inner end of the knob spindle shank 39. This hub structure has an arm 81 extending radially therefrom and a flexible loop or pull member 82 is secured to the outer end of the arm for rotating the spindle. If desired, the hub structure and arm may be enclosed in a bell-shaped housing 83 having an arcuate slot 84 therein and a pin 85 on the outer end of the arm may extend through the slot 84 and have the pull cord 82 attached thereto outside of the housing.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

I claim:

1. A door lock comprising an outer escutcheon structure having a centrally-apertured outer escutcheon plate formation thereon, a latch bolt housing operatively connected at its inner end to said structure, a latch bolt slidably in said housing and having a spindle-receiving opening adjacent the inner end thereof, a knob spindle extending through said outer escutcheon structure and said latch bolt operative upon rotation thereof to retract said latch bolt, an outer knob and an inner knob operatively associated with said knob spindle at corresponding ends thereof, a tumbler barrel and key cylinder in said outer knob, a key spindle having one end connected to said key cylinder and its opposite end extending through said latch bolt to retract the latter upon rotation of said key spindle, a formation on the outer end of said knob spindle locking said spindle and said outer knob against relative rotation, formations on said spindles maintaining said spindles, said outer escutcheon structure and said outer knob in operative association, an inner escutcheon plate surrounding said spindle at

the inner end of said inner knob, means releasably attaching said inner escutcheon plate to said outer escutcheon structure, and locking means carried by said inner escutcheon plate and operatively engageable with said inner knob to restrain said knobs and said knob spindle against rotation to retract said latch bolt.

2. In a door lock, an outer escutcheon structure including a centrally-apertured escutcheon plate formation having a semi-circular flange in the central aperture thereof, and a pair of tongues of partly cylindrical shape having flat inner faces disposed one at each side of said central aperture and provided respectively with screw-threaded wells in the ends thereof opposite said escutcheon plate formation and having longitudinal grooves in said flat inner faces adjacent corresponding edges thereof, a hollow latch bolt housing having shoulders at its inner end slidably received in said grooves, a latch bolt slideable in said housing having in its inner end a spindle slot aligned with said central aperture, a centrally-apertured inner escutcheon plate, screw fasteners threaded into said wells in said tongues securing said inner escutcheon plate to said outer escutcheon structure, a knob spindle extending through the central apertures of said inner and outer escutcheon plates and having a groove therein rotationally interlocking with said semi-cylindrical flange, stop means acting between said latch bolt housing and said latch bolt restraining said knob spindle against rotation sufficient for disassociation thereof from said outer escutcheon plate formation, an outer knob secured on the outer end of said knob spindle, and an inner knob operatively associated with the inner end of said knob spindle.

3. In a door lock, an outer escutcheon structure including a centrally-apertured escutcheon plate formation having a semi-circular flange in the central aperture thereof, and a pair of tongues of partly cylindrical shape having flat inner faces disposed one at each side of said central aperture and provided respectively with screw-threaded wells in the ends opposite said escutcheon plate formation and with longitudinal grooves in said

flat inner faces adjacent corresponding edges thereof, a hollow latch bolt housing having shoulders at its inner end slidably received in said grooves, a latch bolt slideable in said housing having in its inner end a spindle slot aligned with said central aperture, a centrally-apertured inner escutcheon plate, screw fasteners threaded into said wells in said tongues securing said inner escutcheon plate to said outer escutcheon structure, a knob spindle extending through the central apertures of said inner and outer escutcheon plates and having a groove therein rotationally interlocking with said semi-cylindrical flange, stop means acting between said latch bolt housing and said latch bolt restraining said knob spindle against rotation sufficient for disassociation thereof from said outer escutcheon plate formation, an outer knob secured on the outer end of said knob spindle, an inner knob operatively associated with the inner end of said knob spindle, said outer knob having an axial bore and a semi-circular flange in the inner end of said bore, and said knob spindle having a semi-circular flange on its outer end, said knob and spindle flanges having mutually opposing ends when said spindle is operatively associated with said knob to restrain said knob and said spindle against relative rotation.
